UNITED STATES PATENT OFFICE

GABRIEL GRANDJEAN, OF PARIS, FRANCE

FRANKING MACHINE

Application filed March 26, 1925, Serial No. 18,510, and in France April 10, 1924.

This invention relates to a franking machine, characterized

(1) By the fact that it can affix to an envelope either one franking vignette, or successively several vignettes of the same value, or of different values.

(2) By the presence of a special counter which automatically adds up the sum of the values of all these identical or different impressions.

(3) By the presence of a device for preventing fraud by the interposition of carbon paper.

Figure 1 is an elevation of the machine with six values, Figure 2 a section on an enlarged scale of the said machine on line 2-2 of Figure 1. Figures 3 and 4 show in detail the arrangement of the printing system as well as the device which prevents fraud in the case of a machine with a single value. Fig. 5 shows two different impressions made by the stamp.

Description of the general working of the machine

On a spindle 1 carrying the stamps, are keyed two cylinder sectors 2 and 3, on the outer surface of which are the following engravings: On the sector 2, indications of origin and date, advertisements, etc., and on the sector 3 a franking vignette.

A spindle 20 carrying a gear wheel 19 meshing with a gear wheel 12 keyed to the spindle 1, is provided outside the machine with a crank handle 32.

By turning the same handle, the sectors 2 and 3 are rotated. Like in the printing machines called "rotary" presses, the engraved portion of the surface of these sectors starting from their position of rest, first meets an inking roller 8 (Figure 2) which in its turn is in contact with the roller-fountain 8^a; then a rubber pressure roller 9 mounted on springs.

The plane of contact of the surface of the sectors 2 and 3 and of the roller 9 is inclined at an angle of about 45°. To the said plane corresponds an inclined slot or chute 10^a (Figures 2 and 3) into which the packet to be franked is allowed to drop by gravity.

In the position of rest, two or more stops 10 stop the packet at its lower edge in such a manner that the vignette should be printed in a good place on the packet.

To that end, a little before the engraved portion of the sectors 2 and 3 comes in contact with the pressure roller 9, the stops 10 are automatically withdrawn, for instance by the action of a cam 11 keyed to the spindle 20, Figure 2, owing to which the packet can be driven by the rotation of the parts 2, 3 and 9. After the passage between the rollers and after the printing, the packet escapes from the machine at 10^b by gravity.

A modified mechanism for operating the printing mechanism and the stop 10 is shown in detail in Figures 3 and 4.

10^a represents the guide into which the envelope to be stamped is introduced, the guide in question is limited by the edges 70 10^a-10^c. The envelope is stopped by a stop 100 rotatable about a pin A which carries a slide block B with which engages a roller C secured to a bell crank lever D rotatable about a pin E.

The bottom of the envelope rests against a supporting roller 9 loose on a spindle 11^a. This spindle rotates in a bearing 24 (see Figure 10) which can slide in a guide 25, the axis of which is at right angles to that of the 80 guide 10^a. An antagonistic spring 26 tends to bring the bearing 24, Fig. 4, into its end position.

At the opposite side of the guide or chute relatively to the roller 9, is mounted a toothed wheel 12 rotatable about the axle 1 carrying the block 3 in the form of a portion of a cylinder, which prints on the envelope the franking vignette. This stamp passes through an opening provided in the wall 10^c of the guide, the size of the said opening being just sufficient for the passage of the stamp.

The pin E is secured to a slide block 27 which is controlled by a finger 28 rotatable about a spindle 29. This finger is, in turn, 95 operated by a cam 30 mounted on the spindle 1 to which is keyed the toothed wheel 12. An adjustable stop 31 is intended to limit the travel of the finger 28.

Finally on the spindle 20 is keyed a handle 100

32 (the dimensions of which have been reduced for the sake of clearness) which is intended for operating the machine in the following manner:

5 The operation of the handle 32 rotates the wheel 19 which drives the wheel 12 in the direction of the arrow *f*. The stamp 3 comes in contact with its front edge with the envelope after having been impregnated with 10 ink by the roller 8, the lower edge of the envelope being at the stop 100.

At this moment, the pressure roller 9 is pressed by the stamp and the envelope; it will slide therefore, owing to the action of 15 the mechanisms described in the foregoing, to an extent varying according to the thickness of the envelope; moreover whatever be the amplitude of this movement, the antagonistic spring 26 will be sufficient for holding 20 the envelope properly clamped between the stamp and the carrying roller.

At the exact moment the contact of the stamp begins with the envelope, the stop 100 must disappear in order that on the one hand, 25 the stamp should not slide on the envelope, and on the other hand, in order that the stamp should not be stopped by the stop. This disappearance takes place owing to the action of the cam 30, the shape of which is such that 30 it lowers, by means of the mechanisms previously described, the stop 100 until it is brought into the position shown dotted in Figure 9. The stop is held in that position until the end of the operation by cam 30.

35 At this moment the platen roll moves in an opposite direction; the envelope being no longer pressed between the stamp and the roller, and being no longer stopped by the stop 100, will slide along the guide and escape 40 from the machine.

If the movement of the hand wheel continues, a moment will arrive in which the finger 28 which follows the outline of the cam will cause the stop, by means of the parts 45 previously described, to make a rising movement which will bring it into the position which it occupied when the envelope was introduced.

50 *Detail of the printing device and of the fraud-preventing devices*

It is important to design the machine so as to make impossible the two kinds of fraud, consisting:

55 (1) The printing of the vignette by means of the inked stamp without the operation being registered by the totalizer.

(2) In stamping simultaneously several envelopes by inserting between them sheets of 60 carbon paper.

To that end, the damp stamp must be inaccessible, and on the other hand a dry plug is combined with the figures printed by the damp stamp so as to render any fraud visible.

65 This latter device consists in causing to pro-

ject from the printing surface, at the exact moment of printing, the ends of pins or plugs which during the inking were on the contrary, withdrawn.

These ends are therefore not inked and 70 leave a white space in the lines of the vignette which they intersect; if a second envelope is under the first one, with a carbon interposed, at the moment of the passage between 3 and 9 (Figures 3 and 5), the ends 75 of the pins will energetically press the carbon paper against the second envelope, and in the second impression, the interruptions of lines will be filled up by the impression of the ends of the pins, produced by the carbon paper. These devices are shown in Figures 3 and 5 which relate to a machine printing a single value. It will be seen later on what modifications are required to enable them to be applied to a machine with multiple value. 85

In the centre of the stamp is provided an opening 15 which affords passage to a sliding rod 16, the axis of which coincides with a diameter of the wheel 72. This rod 16 is 90 provided with a head 17 which projects outside the wheel, at the side opposite to that of the opening 15. Against the head of the rod presses a spring 18 which normally holds the rod in such a manner that it does not project through the opening 15, so that its end 95 does not get inked when the stamp passes over the roller.

The toothed wheel 72 engages with the second toothed wheel 119. On the spindle of the wheel 119 is mounted an eccentric 21 intended to act on the head of the said rod. 100

When the hand wheel 32 is operated, the head 17 of the rod 16 comes in contact with the eccentric 21. The rod is therefore pushed in, and its lower end is pressed against the envelope at the same time as the vignette. The printing of the vignette proceeds then by the movement of the hand wheel and is finished when the rear edge of the stamp leaves the envelope. At this moment the head of the rod 16 has left the eccentric 21. The machine is therefore in its initial position, and a new envelope can be then stamped by proceeding in the same way. 110

It will be seen therefore that if several envelopes separated from each other by sheets of carbon paper, were introduced simultaneously into the slot of the machine, only the first envelope would be stamped correctly; the envelopes under it would show, with the device shown, in the central portion of the vignette a stain having the outer shape of the lower end of the rod 16. The shape of this impression as well as its position can be varied. For instance the arrangement could be made in such a manner that the said impression would have the shape of the letters or numbers of the vignette (see Figure 5). 120

It will be then absolutely impossible to rub out these impressions, or to cut out the sheets of carbon paper in such a manner that they should leave free the outlines of the impression.

As regards fraud consisting in pressing the envelope against the stamp without operating the machine, it will be seen that this is impossible as in the position of rest of the machine and also in the stamping position the stamp is in an absolutely inaccessible position.

In order to prevent any possibility of pressing envelopes against the stamp while the latter is in the printing position, two springs H are disposed at either side of the said stamp, which springs allow only a very narrow portion of the stamp to be accessible and which assume the dotted position during printing.

20 A device enabling vignettes of different values to be printed

This device consists (Figures 1 and 2) of a cylinder 3 comprising a fixed portion 33 and two cheeks 34 and 35. The part 33 has a cylindrical recess which contains a hexagonal prism 36 with curved faces, each of which is provided with a different engraving, the curvature of the faces being the same as that of the cylinders 2 and 3.

The hexagonal prism 36 can pivot between the two cheeks 34 and 35; it is provided for the purpose with a toothed wheel 37 which can be driven by means of the following parts:

On a spindle 38 parallel to the spindles 1 and 20, is keyed a toothed wheel 39 identical with the wheel 37. The end of the spindle 38 which projects out of the machine, terminates in a hexagon 40, each face of which bears the indication of one franking value. A helical spring 41 holds the hexagon in a hexagonal recess of the frame, and in that position the wheel 39 does not engage with the wheel 37.

The mechanism being in its position of rest, it is sufficient to pull the button-hexagon 40 in order to pull it out of its recess where it was locked, and to bring into engagement the two gear wheels 39 and 37.

50 A suitable turning of the spindle 38 brings the desired vignette to the printing cylindrical face.

During these movements, various locking bolts will work which will be described further on, and ensure security of the operation.

In the case of the machine with multiple values, the security device preventing impression by carbons, has been built as follows (Figures 1 and 2): the two pins 16 of one and the same vignette are connected together in the form of a shackle 68 introduced into its recess through the interior of the engraved block which is hollow. An

eccentric inner cylinder 69 pushes all these shackles towards the periphery, a suitable device such as a ring or springs keeps the shackles in contact with the eccentric. The eccentricity is such that all the ends of the pins are set back or withdrawn except for that of only one shackle.

On the end of the eccentric cylinder is keyed a wheel 70 which meshes with a similar wheel 71 secured to the frame and concentric with the spindle 1.

During the rotation of the stamp-carrying spindle, the wheel 70 rotates about 71 and also makes one revolution about its axis; the eccentric cylinder to which it is secured, therefore makes all the pins of the engraved surface project successively. To obtain the desired result, it will be sufficient to key the wheels 70 and 71 in such a manner that on the vignette utilized, the pins should be projected at the passage over the rubber roller 9.

Changing the vignette

As regards the changing of vignette, it can only be done by means of the button 40' which can be turned when the hexagon has been withdrawn from its recess.

This operation can be effected only in the position of rest owing to the following mechanism. In that position of rest, a lever 46 in engagement with a grooved disc 47 on the end of the spindle 38, can engage with a recess 48 of the disc 49 keyed to the shaft 20. The operation of this spindle is thus rendered impossible during the changing of a vignette, and conversely.

The button 40' having thus been brought to the left hand end of its travel, and the whole mechanism locked, the two pinions 37 and 39 will be in engagement. On the other hand, a locking bolt 50 which locked the toothed wheel 37 relatively to the printing sector 33 by engaging with a recess of the wheel 37, is brought to the position of rest by operating the pinion 39 (see Figure 1); the block of the vignettes is therefore ready to obey the impulse that will be given to it by the outer button.

The turning of the button 40' necessarily produces, at the same time as the change of stamp, a longitudinal movement of the nut 43 on the screw 42, proportional to the pitch of the screw and to the fraction of revolution made; these factors are calculated so that the loose gear 44 shall engage with the toothed wheel corresponding to the stamp selected, the value of which appears alone in the window 51.

It will be seen therefore that both before and after the vignette changing operation, the engraved block is never left to itself. The dimensions of the parts and their adjustment are such that the wheel 37 is neces-

sarily either locked by 50 or in engagement with the pinion 39.

Various devices

5. First of all, the rotation of the crank handle 32 must be made non-reversible so as to prevent the counter from registering in the negative sense.

To that end, a wheel 53 is provided with a 10 ratchet device. Moreover, a pawl 54 doubles this security by engaging with a recess 48 of a disc 49 secured to the spindle 20, at the moment when only half of the vignette has been printed.

15. *Claims:*

1. A franking machine comprising a stamping roller, a stamp on said roller, a guide roller for said stamp, means for guiding envelopes between said stamping roller and said guide roller and means carried by said first mentioned roller for preventing true carbon impressions from being made from said stamp.

2. A franking machine comprising a stamping roller, a stamp on said roller, a guide roller for said stamp, means for guiding envelopes between said stamping roller and said guide roller and means including a radially operated pin associated with said first mentioned roller for preventing true carbon impressions from being made from said stamp.

3. A franking machine comprising a stamping roller, a stamp on said roller, a guide roller for said stamp, means for guiding envelopes between said stamping roller and said guide roller and means for altering a carbon impression made from said stamp without altering the original impression made therefrom.

4. In a franking machine of the type described a stamping roller, a plurality of stamps carried by said roller, means for bringing said stamps successively into operative position, a radially disposed pin slidably mounted in each of said stamps, a guide roller for said stamping roller, means for guiding envelopes between said guide roller and said stamping roller and means for causing each of said pins to move outwardly when its respective stamp is in contact with said guide roller.

5. In a franking machine of the type described, a stamping roller, a plurality of stamps carried by said roller, means for bringing said stamps successively into operative position, a radially disposed pin slidably mounted in each of said stamps, a guide roller for said stamping roller, means for guiding envelopes between said guide roller and said stamping roller and an eccentric for causing each of said pins to move outwardly when its respective stamp is in contact with said guide roller.

6. In a franking machine of the type de-

scribed, a stamping roller, a hexagonal prism mounted in said stamping roller, a plurality of vignettes carried by the surfaces of said prism, means for bringing said vignettes successively into operative position, a centrally disposed recess in said prism, a plurality of normally retracted plungers in said prism having their ends projecting into said recess, a guide roller for said stamping roller, means for guiding envelopes between said guide roller and said stamping roller and means for causing each of said plungers to move outwardly when its respective vignette is in contact with said guide roller.

7. In a franking machine of the type described, a manually operated spindle, a stamping roller mounted on said spindle, a plurality of stamps carried by said roller, means for bringing said stamps successively into operative position, a radially disposed pin slidably mounted in each of said stamps, a guide roller for said stamping roller, means for guiding envelopes between said guide roller and said stamping roller, an eccentric associated with said pins and means driven by said spindle for causing the pin whose stamp has been moved to operative position to move outwardly when said stamp is in contact with said guide roller.

8. In a franking machine of the type described which comprises a frame, a main spindle mounted in said frame, a second spindle driven by said first mentioned spindle, a printing cylinder mounted on said second spindle, a rotatably mounted prism having curved surfaces carried by said cylinder, a plurality of vignettes of different values on said curved surfaces, a third spindle mounted in said frame, means for operatively connecting said third spindle and said printing cylinder for successively bringing said vignettes into operative position, a manually controlled knob mounted on said third spindle exterior of said frame and locking means controlled by said connecting means for holding said prism in a fixed position with respect to said printing cylinder when said vignettes are not being changed.

9. In a franking machine of the type described which comprises a frame, a main spindle mounted in said frame, a second spindle driven by said first mentioned spindle, a printing cylinder mounted on said second spindle, a rotatably mounted prism having curved surfaces carried by said cylinder, a plurality of vignettes of different values on said surfaces, a third spindle mounted in said frame, means for biasing said third spindle normally to an inoperative position, a pinion carried by said third spindle, a second pinion carried by said prism, locking means normally holding said second pinion in a fixed position with respect to said printing cylinder and means on said first mentioned

pinion for releasing said locking means when said first and second pinions are in mesh.

10. A franking machine as set forth in claim 8, in which means are associated with said main spindle for preventing operation thereof when said third spindle is moved to an operative position.

11. A franking machine as set forth in claim 8 in which said main spindle is provided with a locking disc, a lever associated with said locking disc and means on said third spindle for releasing said locking lever when said third spindle is moved to an inoperative position.

15. 12. In a franking machine of the type described having, a printing roller, a substantially annular stamp drum mounted in said roller and a guide roller for said stamping roller, the combination of a plurality of radially disposed U-shaped members slidably mounted in said stamp drum, an eccentric mounted in said stamp drum, flexible means common to said U-shaped members for maintaining said U-shaped members in engagement with said eccentric and means for producing rotation of said eccentric with respect to said stamp drum when said stamp drum is rotated for the purpose described.

30 13. In a franking machine of the type described having, a printing roller, a substantially annular stamp drum mounted in said roller and a guide roller for said stamping roller, the combination of a plurality of radially disposed U-shaped members slidably mounted in said stamp drum, an eccentric mounted in said stamp drum, flexible means common to said U-shaped members for maintaining said U-shaped members in engagement with said eccentric, a pinion carried by said eccentric and a stationary pinion coaxially disposed with respect to said printing drum meshing with said first mentioned pinion for the purpose disclosed.

45 14. In a franking machine of the type described having, a printing roller, a substantially annular stamp drum mounted in said roller and a guide roller for said stamping roller, the combination of a plurality of radially disposed U-shaped members slidably mounted in said stamp drum, an eccentric mounted in said stamp drum, an endless coiled spring disposed within and surrounding said U-shaped members for maintaining said U-shaped members in engagement with said eccentric and means for producing rotation of said eccentric with respect to said stamp drum when said stamp drum is rotated for the purpose described.

60 15. In a franking machine of the type described having, a printing roller, a substantially annular stamp drum mounted in said roller and a guide roller for said stamping roller, the combination of a plurality of radially disposed U-shaped members slidably mounted in said stamp drum, an eccentric

mounted in said stamp drum, an endless coiled spring disposed within and surrounding said U-shaped members for maintaining said U-shaped members in engagement with said eccentric, a pinion carried by said eccentric and a stationary pinion coaxially disposed with respect to said printing drum meshing with said first mentioned pinion for the purpose disclosed.

70 In testimony that I claim the foregoing as my invention, I have signed my name.

GABRIEL GRANDJEAN.
